(57) CLAIM

The ornamental design for a hairspray face shield, as shown and described.

DESCRIPTION

FIG. 1 is a top, front, right side, perspective view of the hairspray face shield of the present invention;

FIG. 2 is a front elevational view of the hairspray face shield of FIG. 1;

FIG. 3 is a rear elevational view of the hairspray face shield of FIG. 1;

FIG. 4 is a right side elevational view of the hairspray face shield of FIG. 1, the left view being a mirror image thereof;

FIG. 5 is a top plan view of the hairspray face shield of FIG. 1; and,

FIG. 6 is a bottom plan view of the hairspray face shield of FIG. 1.
